UNITED STATES PATENT OFFICE.

THOMAS T. PEDDY, OF BIENVILLE, LOUISIANA.

DEFLECTOR.

1,075,062.

Specification of Letters Patent.

Patented Oct. 7, 1913.

Application filed July 19, 1912. Serial No. 710,484.

To all whom it may concern:

Be it known that I, THOMAS T. PEDDY, a citizen of the United States, residing at Bienville, in the parish of Bienville and State of Louisiana, have invented new and useful Improvements in Deflectors, of which the following is a specification.

This invention relates to deflectors for car windows, the object in view being to 10 provide an exceedingly simple, cheap and effective fastener for securing deflectors to car windows, and enabling the same to be reversed and applied either at the front or at the back of any individual window of the 15 car, the deflector itself being of such construction as to cause an outward movement of the cinders, dust and other flying material, while also inducing an outward current of air from the interior of the car, thereby 20 not only preventing the cinders from reaching a person sitting adjacent to the window, but also effecting a thorough but gradual ventilation of the car.

With the above and other objects in view, 25 the invention consists in the construction, combination and arrangement of parts, as will be hereinafter more fully described, illustrated in the accompanying drawings, and pointed out in the claims hereunto 30 appended.

In the drawings: Figure 1 is a horizontal section through a sufficient portion of a car, including a car window, to show the improved deflector applied thereto. Fig. 2 is a 35 vertical section through the deflector, and a portion of the car window, showing the improved fastening device applied thereto. Fig. 3 is a perspective view of the deflector. Fig. 4 is a similar view of the fastening 40 device as applied to a window frame.

The deflector is shown as made up of a single blank of sheet metal, the deflector portion 1 being concavo-convex in horizontal cross section, while the body 2, which is 45 mensurate in length with the deflector portion 1, is doubled upon itself, as shown at 3, to provide a base of double thickness, which will adequately support the car window which rests directly upon the upper 50 edge of the body 2, when the deflector as a whole is in its operative position, the lower edge of said body 2 resting upon the car sill, while the deflector portion 1 extends beyond the plane of the car body.

55 In carrying out the present invention, I employ a keeper plate 4 which is fastened

rigidly to the jamb of the window frame at two points 5, thus rendering it impossible for said keeper plate to move in any direction. At its upper end, the keeper plate is 60 offset outwardly, as shown at 6, to form an upwardly extending retaining lip 7 for engagement with the base 2 of the deflector. The fastener also comprises a pivoted button 8, the same being pivotally connected to 65 the keeper plate 4, at the point 9. The length of the button 8 is such that the lower end thereof, when the button is swung downward, projects beyond the lower end of the keeper plate 4, as shown clearly in Figs. 2 70 and 4. The button 8 is provided with an outwardly projecting knob 10 to facilitate turning said button from its pendent position to an upright position.

The base 2 of the deflector is provided 75 with a slot 11, the width of which is just sufficient to allow the base 2 to pass over the keeper plate 4, and bear against the jamb 12 of the car window. The length of the slot 11 is slightly in excess of the total 80 length of the keeper plate 4, including the retaining lip 7, in order that the base 2 may be placed over the keeper plate, and then slid downward until the retaining lip 7 bears against the outside of the base 2 85 just above the upper extremity of the slot 11, as shown in Fig. 2. The button 8 is of such length that when the base 2 has been slid down behind the lip 7, the lower end of the button, when the latter is swung 90 downward, will rest against the side of the base 2 and confine the same against the jamb of the window frame, as clearly shown in Fig. 2.

From the foregoing description, it will 95 now be understood that the deflector is reversible, or in other words, said deflector may be turned either end up, so that it may be applied to either side or jamb of the window frame. This adapts the deflector to 100 a car moving in either direction, one of said fasteners being applied to each window jamb, so as to admit of the interchangeability of the deflector from one side of the window to the other.

105 What is claimed is:

A deflector for the purpose stated, comprising a flat base provided with a slot therein, a concavo-convex body extending outwardly from the base, a keeper plate 110 adapted to be fixedly attached to a car window frame and to be received in the slot

in the base of the deflector, an outwardly offset deflector retaining lip formed integrally with one end of the keeper plate, and a turn button pivotally mounted on said keeper plate and also adapted to pass through said slot and to project at one end beyond the opposite end of the keeper plate from the retaining lip thereof, both of said lips being adapted to engage the outer face

of the deflector base and lock the same to 10 the frame.

In testimony whereof I affix my signature in presence of two witnesses.

THOMAS T. PEDDY.
